UNITED STATES PATENT OFFICE.

DENNIS W. SMITH, OF WILMETTE, ILLINOIS, ASSIGNOR TO COLBORNE MANUFACTURING COMPANY, OF CHICAGO, ILLINOIS, A CORPORATION OF ILLINOIS.

DISCHARGE MECHANISM FOR PIE MACHINES AND THE LIKE.

Application filed May 28, 1927. Serial No. 194,991.

This invention relates to improvements in the ejector mechanism for pie machines and the like; and one of the main objects is to provide an ejector which can be swung about 5 to discharge the pies in whichever direction it may be desired.

The ejector mechanism is substantially the same as the mechanism shown in my copending application, Serial No. 56,282, filed September 14, 1925, now Patent No. 1,671,321, granted May 29, 1928, and the means for swinging the ejector to discharge at different stations are shown herein.

The pie making machine is quite large and 15 bulky, and is usually installed in close quarters wherein it is not always possible to set the machine to discharge in the proper direction if the ejector is fixed. Accordingly, in this invention, the frame or base member 20 is pivotally mounted so it may be swung in any direction.

An illustrative embodiment of this invention is shown in the accompanying drawings, in which:

25 Fig. 1 is a plan view of the delivery end of the machine.

Fig. 2 is a side elevation of Fig. 1, with parts omitted and parts broken away.

Fig. 3 is a detail section of the parts mounted on the vertical drive shaft, and taken as indicated by line 3—3 in Fig. 1.

The pies 1 are formed in pie tins which are placed on the supports 2 at the left side of the machine. The supports are carried 35 by an endless conveyor built up of the jointed links 3, which are supported at either side of the machine frame 4 and are engaged on the horizontal sprocket wheels 51, which are mounted at either end of the frame 4.

40 As the pie tins travel along the left side of the machine and return along the right side, the crusts and filler are deposited in the tins, and the crust is trimmed. The pies are then delivered from the end of the machine, 45 which is shown, ready for baking.

The supports 2 are mounted on the horizontal disks 5 which are mounted on the sleeves 6 in every second joint of the conveyor. A lifter disk 7, which normally rests on the 50 disk 5, is provided with a rod 8, which is slidable in the sleeves 6 and projects from the lower end thereof.

In discharging, the lower end of the rod 8 rides up on the cam rail 9, which is supported 55 below the sprocket 5, and the pie tin with

the finished pie thereon is lifted out of the support 2 in position to be engaged by the horizontally reciprocating ejector plate 10 and moved laterally onto the conveyor belt 11.

The sprocket wheel 51 is mounted on the vertical shaft 12, which is rotatably supported by the arm 13 which is attached to the machine frame 4. The shaft 12 is driven by a worm on the drive shaft 14, which meshes with a worm gear 16, secured on the lower 60 end of the shaft 12.

The base 17 of the ejector rests on the top of the arm 13 and is pivoted on the shaft 12. The base 17 is locked in any desired rotative position by means of the cap screw 18, suitable tapped holes being of course provided in the arm 13.

The ejector plate 10 is carried on the end of the bar 19, which is slidable in the guide member 20 which is mounted on the upwardly projecting arms 21 of the base 17. For reciprocating the bar 19, a lever 22 is connected at one end to a plate 23, secured on the base 17, by means of a link 24. The mid portion of the lever 22 is pivoted on the crank pin 25 70 of the crank arm 26; and the other end of the lever is slidably engaged with the bar 19.

The crank arm is keyed on a stub shaft 26, which is rotatably mounted in the base 17, and is rotated by means of the pinion 27, 80 keyed on the shaft, which meshes with a spur gear 28 which is keyed on the upper end of the sprocket wheel shaft 12.

Since a pie is carried on each quadrant of the wheel 51, the gear 28 is four times as large 90 as the pinion 27. Thereby the ejector cooperates with each pie support, and will register in any position the base is rotated, after it has been properly timed for one position.

Although but one specific embodiment of this invention has been herein shown and described, it will be understood that numerous details of the construction shown may be altered or omitted without departing from 95 the spirit of this invention as defined by the following claims:

I claim:

1. In a pie machine, a pie conveyor mounted to move in a circular path about a fixed center, and ejector means for removing the pies from the conveyor, said means being mounted for rotation about said center and having a positive driving connection with the conveyor.

2. In a pie machine having pie supports mounted to travel in a circular path about a fixed center, ejector means cooperating with said supports to remove the pies, said means being mounted so that it may be adjustable about said center.
3. In a pie machine having pie supports mounted to travel about a fixed center, ejector means for cooperating with said supports, said means being mounted for adjustment about said center and having a positive driving connection with said supports so as to register with each support in any of the adjusted positions.
4. In a pie machine having a vertical shaft and a conveyor for pie supports carried by a wheel fixed to the shaft, an ejector support adjustably rotatable on the shaft, a gear keyed on the shaft, a pinion mounted on the ejector support and meshed with the gear, and ejector

means for removing the pies from the supports, said means being mounted on the second mentioned support and having a positive driving connection with the pinion.

5. In a pie machine having a conveyor for a pie support carried on a wheel fixed to a shaft, ejector means for removing the pie from said support, said means having a positive driving connection with the shaft and adjustably pivoted thereon so that it may be set to discharge the pies in various directions.

6. In a pie machine having a conveyor for a pie support carried on a wheel fixed to a shaft, ejector means for removing the pie from the support, said means having a base which is adjustably supported on said shaft, and being operatively connected to the shaft.

Signed at Chicago this 26 day of May, 1927.

DENNIS W. SMITH.
